UNITED STATES PATENT OFFICE.

THOMAS F. SCOLLARD, OF WARSAW, INDIANA.

ROTARY VALVE.

1,389,536.

Specification of Letters Patent. Patented Aug. 30, 1921.

Application filed June 22, 1920. Serial No. 390,741.

To all whom it may concern:

Be it known that I, THOMAS F. SCOLLARD, a citizen of the United States, residing at Warsaw, in the county of Kosciusko 5 and State of Indiana, have invented a new and useful Rotary Valve, of which the following is a specification.

The present invention has reference to valve constructions, and more particularly 10 to a novel form of valve of the rotary type, to be employed in connection with internal combustion engines.

The primary object of the invention is to provide a rotary valve having a novel form 15 of cooling means whereby a cooling fluid may be circulated through the valve proper to maintain the valve cool, thereby eliminating sticking of the contacting members of the valve.

20 A further object of the invention is to provide means within the valve for retaining water therein, for a predetermined period, to insure the cooling fluid contacting with the entire inner surface of the valve.

25 With the foregoing and other objects in view which will appear as the description proceeds, the invention resides in the combination and arrangement of parts and in the details of construction hereinafter 30 described and claimed, it being understood that changes in the precise embodiment of the invention herein disclosed, may be made within the scope of what is claimed, without departing from the spirit of the invention.

35 Referring to the drawing:—

Figure 1 illustrates a longitudinal sectional view through a valve constructed in accordance with the present invention.

40 Fig. 2 illustrates a transverse sectional view taken on line 2—2 of Fig. 1.

Having reference to the drawing in detail, the reference character 5 designates the casing of the valve which is provided with 45 a flanged portion 6 formed integral with the lower extremity thereof, which flanged portion is provided with suitable openings 7 to accommodate the securing members 7 which also pass through suitable openings 50 formed in the flange 9 of the base 10.

The casing 5 includes the spaced outer walls 11 and inner walls 12, providing a continuous passage between the walls of the casing, the passageway being indicated by 55 the reference character 13 and is in com-

munication with the passageway 14 formed in the base 10, whereby the lower extremity of the valve proper may be cooled.

The inner surface of the casing is tapered to conform to the taper of the removable 60 sleeve 15, which is disposed within the casing, the upper extremity thereof being supported in spaced relation with the removable cover 16 which as shown is bolted to the casing as at 17.

65 The valve member includes the tapered wall 18 which contacts with the inner surface of the sleeve member 15 and as shown, this wall 18 is provided with an offset portion 19 disposed in spaced relation with the 70 sleeve 15, to reduce the wear surface between the sleeve and wall 18.

75 Forming a part of the valve member is a central pipe section 20, which provides means of communication between the feed pipe 21 and the discharge port 22, however it is to be understood that the feed pipe 21 discharges into the pocket 23 formed at the upper end of the valve. The upper edge of the pipe 20 is inclined as at 24, 80 while the opposed wall is inclined as at 25, to provide a tapered seat for the boss 26 which is also provided with inclined edges 25 to insure a water-tight connection between the upper end of the valve and the cover 27.

85 An opening 27' is formed in the cover 27, whereby steam generated in the valve member may mingle with the incoming gases to 90 moisten the same.

95 The space between the pipe 20 and the wall 18 of the valve, provides a water passageway for permitting the water to pass into close contact with the valve proper to cause the cooling of the surface thereof. Communicating with the water passageway, and extending through the cover 27, is a 100 feed pipe 28 which has connection with a suitable water supply, whereby water may be fed to the valve member, the water passing through the valve member and passing outwardly therefrom through the pipe 29, where the same exhausts.

105 In order that the water will be maintained within the valve member, for a predetermined period, a partitioning sleeve 30 is provided, and as shown, this partitioning sleeve extends from the lower portion of the valve, upwardly, terminating at a point sub- 110

stantially intermediate the ends of the valve proper, the sleeve being disposed in spaced relation with both the pipe 20 and the inner surface of the offset portion 19.

5 Formed in the lower end of the pipe 20, is an opening 31 adapted to receive the key 32 for connecting the drive shaft 33 and the inner valve member, the drive shaft 33 being however, operated by suitable gearing, 10 to cause the port 34 of the valve proper to register with the ports 35 and 36 of the sleeve and valve casing respectively.

15 Packing rings 37 are carried by the valve member proper, adjacent to the upper end thereof, which packing rings insure an absolute water-proof connection between the valve proper and the removable sleeve 15, the rings however being supported at the upper end of the valve proper, or at a point 20 where the wear between the valve and its sleeve, is the greatest.

25 It might be further stated that a valve spring 37 is disposed between the cover 16 and cover 27, the spring being of the coil type and embraces the pin 34 so that the cover 27 is urged into close engagement with the upper portion of the valve proper to insure against water or the cooling fluid passing into the valve member, and into the 30 pocket 23.

35 In the operation of the device, the valve proper is rotated as heretofore described, and water passes into the passageway between the inner surface of the valve and outer surface of the pipe 20, whereupon the same flows over the upper edge of the sleeve 30 and passes outwardly through the pipe 29.

40 It is believed that in view of the foregoing description, a further detail descrip-

tion as to the operation of the device is unnecessary.

What is claimed as new is:—

1. In a rotary valve, a casing, a valve member positioned within the casing, means for rotating the valve member, a sleeve interposed between the valve member and casing, means for supplying a cooling fluid to the interior of the valve member, a sleeve disposed within the valve member, said sleeve adapted to retain a portion of the cooling fluid within the valve member, a cover covering the upper portion of the valve member, means to permit movement of the valve member with relation to the cover, and a discharge pipe for carrying off the cooling fluid. 45

2. In a rotary valve, a casing, a valve member positioned within the casing, means for rotating the valve member, a sleeve interposed between the valve member and casing, means for supplying a cooling fluid to the interior of the valve member, said sleeve adapted to retain a portion of the cooling fluid in the valve member, said sleeve being disposed adjacent to the bottom of the valve member and extending upwardly terminating at a point substantially intermediate the ends of the valve member, a cover covering the upper portion of the valve member, and a discharge pipe for carrying off the cooling fluid. 50

60 In testimony that I claim the foregoing as my own, I have hereto affixed my signature in the presence of two witnesses.

THOMAS F. SCOLLARD.
